United States Patent Office

Des. 188,198

Patented June 14, 1960

188,198

MIRROR

Ernest L. Swarts and Orville B. Solie, Rockford, Ill., assignors to The Lane Company, Inc., Altavista, Va., a corporation of Virginia

Filed June 24, 1959, Ser. No. 56,529

Term of patent 14 years

(Cl. D33—9)

The figure is a perspective view of a mirror showing our design.

The rear of the mirror is conventionally plain.

We claim:

The ornamental design for a mirror, as shown and described.
